UNITED STATES PATENT OFFICE.

VINCENT BENDIX, OF CHICAGO, ILLINOIS.

ENGINE-STARTER.

1,274,371.

Specification of Letters Patent.

Patented Aug. 6, 1918.

Application filed October 30, 1916. Serial No. 128,478.

To all whom it may concern:

Be it known that I, VINCENT BENDIX, a citizen of the United States, residing at Chicago, in the county of Cook and State 5 of Illinois, have invented certain new and useful Improvements in Engine-Starters, of which the following is a specification.

My invention relates to a starter for an engine, such as a gas engine, and pertains 10 to the transmission or drive interposed between the starting motor and a part of the engine to be started. The drive herein described and claimed embodies as a material part of its organization that type of drive 15 or transmission exemplified in patents heretofore issued to me, for instance, Patent No. 1,125,935, dated January 26, 1915, and Patent No. 1,172,864, dated February 22, 1916. This type of engine starter is characterized 20 by a prime mover (such as an electric motor or motor-generator of the two unit and single unit starter systems respectively), and a transmission or drive for transmitting the power of the motor by means of a rotatable 25 member, such as a screw shaft, and a driving member such as a pinion mounted thereon, for transmitting the power of the motor to some member or part of the engine to be started, such as the fly-wheel thereof.

30 My present invention consists in combining with said type of drive or transmission suitable reduction gearing between such drive and the engine part, such as the fly-wheel, it being understood that in the organization in which my invention is embodied the pinion of the regular drive does not mesh with the fly-wheel but with the reduction gearing which in turn meshes with the fly-wheel. In this manner and by these 35 means I am enabled to provide a simple and efficient transmission having a reduction gearing intermediate the regular drive and the fly-wheel instead of between the motor and the screw shaft.

40 In the drawing the single figure is a sectional elevation, the regular transmission or drive being in elevation and the reduction gearing and associated parts in section.

The construction and mode of operation 45 of the regular or standard Bendix drive embodied in the organization about to be explained are the same as that set forth in my patents aforesaid with the exception that the pinion does not mesh with the reduction 50 gearing. It will therefore be sufficient to merely designate the principal parts by ref-

erence numerals as follows: 1 is the extended armature shaft mounted in a bearing a of a casing A which is attached to the starting motor indicated at B, or otherwise supported. 2 is the hollow screw shaft on this extended armature shaft, 3 the pinion or gear screw threaded on the screw shaft, and 4 the spring driving connection between the outer end of the shaft 1 and the driving 65 head 2^a .

The new or additional portion of the new organization of drive comprises reduction gearing or so-called double reduction which here consists of a gear and pinion operated 70 and controlled in their movements, both rotary and longitudinal, by the pinion 3 of the regular drive, whereby such gearing is adapted to be meshed with the gear teeth 5 a of a fly-wheel 5 or other rotatable part of 75 the engine to be started.

Describing the reduction gearing in detail, the same consists of a gear 6 which in practice is twice the diameter of the pinion 3. This gear has a hub or sleeve portion 7 80 which carries a pinion 8 which by preference is formed as an integral part thereof. This gear and pinion are mounted upon the stationary shaft 9 and are capable of both rotary and longitudinal movements thereon. 85 This shaft is supported at its outer end in the bearing a' of the casing A and at its inner end in the boss b of the starting motor casing. This gear and pinion are held in its normal or home position to the right as 90 shown in the drawing, with a yielding pressure as by means of the coiled spring 10 which holds the pinion 8 against the distance sleeve 11.

Describing the mode of operation and 95 starting with the parts in their normal position shown in the drawing, the pinion 3 will be advanced longitudinally toward the left on the screw shaft when the motor is started and the screw shaft thereby caused to rotate. After the pinion has come into full mesh with the gear 6 the disk 3^a of the pinion 3 will contact the right hand side of the gear 6 and as the pinion 3 continues to advance, such gear will be moved bodily 100 toward the left against the tension of the spring 10. As a result the pinion 8 will be moved into mesh with the fly-wheel gear 5 a and this longitudinal movement will continue until the pinion 3 comes into contact 110 with the stop nut 12 on the screw shaft, whereupon the pinion will rotate in unison

with the screw shaft and consequently the reduction gearing will likewise rotate and thereby cause the rotation of the flywheel. When the engine starts on its own power 5 the pinion 3 will be automatically moved longitudinally toward the right and the spring 10 will move the gear in that same direction, and consequently the pinion 8 will be demeshed with the fly-wheel. The 10 parts thereupon assume their normal position shown in the drawing.

It is evident that my invention is applicable to both the two and single unit types of starters and, therefore, while I have 15 spoken of the motor B merely as a starting motor, it will be understood that the same may be a motor-generator of the two unit type.

I claim:

20 1. In a drive of the character described, the combination of a rotatable member, a driving member mounted thereon for rotary movement therewith and longitudinal movement thereon, and normally inoperative reduction means between such driving member and a part of the engine to be started and controlled by and made operative when the driving member is actuated.

2. In a drive of the character described, 30 the combination of a rotatable member, a driving member mounted thereon for rotary movement therewith and longitudinal movement thereon, and reduction gearing intermediate such driving member and a part 35 of the engine to be started, said gearing being normally out of operative engagement with both of them but controlled by said driving member.

3. In a drive of the character described, 40 the combination of a rotatable member, a driving member mounted thereon for rotary movement therewith and longitudinal movement thereon, and reduction gearing intermediate the driving member and a part of 45 the engine to be started and mounted for bodily movement longitudinally, said gearing being located in the path of movement of the driving member and moved longitudinally thereby.

50 4. In a drive of the character described, the combination of a rotatable screw shaft, a pinion mounted thereon for rotary movement therewith and longitudinal movement thereon, and normally inoperative reduction 55 gearing intermediate such pinion and a part of the engine to be started and controlled by and made operative when the pinion is actuated.

5. In a drive of the character described, 60 the combination of a rotatable screw shaft, a pinion mounted thereon for rotary movement therewith and longitudinal movement thereon, and reduction gearing intermediate such pinion and a part of the engine to be 65 started, said gearing being normally out of

engagement with the pinion and engine part but arranged to be engaged therewith by the longitudinal movement of such pinion.

6. In a drive of the character described, 70 the combination of a rotatable screw shaft, a pinion mounted thereon for rotary movement therewith and longitudinal movement thereon, and reduction gearing intermediate such pinion and a part of the engine to be started, said gearing being mounted for 75 bodily movement longitudinally to bring it into engagement with said engine part and being engaged by the pinion on its longitudinal movement and subsequently rotated thereby.

7. In a drive of the character described, 80 the combination of a rotatable screw shaft, a pinion mounted thereon for rotary movement therewith and longitudinal movement thereon, and reduction gearing intermediate 85 such pinion and a part of the engine to be started, said gearing being mounted for bodily movement longitudinally and comprising a gear and a second pinion controlled and operated thereby, the former 90 being adapted to engage the engine part, and the latter being adapted to be moved longitudinally and subsequently rotated by the first pinion.

8. In a drive of the character described, 95 the combination of a rotatable screw shaft, a pinion mounted thereon for rotary movement therewith and longitudinal movement thereon, and reduction gearing intermediate such pinion and a part of the 100 engine to be started, said gearing being mounted for bodily movement longitudinally and comprising a gear and a second pinion controlled and operated thereby, the former being adapted to engage the 105 engine part, and the latter being adapted to be moved longitudinally and subsequently rotated by the first pinion, and means for restoring the gearing to normal position.

9. In a drive of the character described, 110 the combination of a rotatable screw shaft, a pinion mounted thereon for rotary movement therewith and longitudinal movement thereon, and reduction gearing intermediate 115 such pinion and a part of the engine to be started, said gearing being mounted for bodily movement longitudinally and comprising a gear and a second pinion controlled and operated thereby, the former being 120 adapted to engage the engine part, and the latter being adapted to be moved longitudinally and subsequently rotated by the first pinion, and a spring acting on the gearing for restoring it to normal position.

10. In a drive of the character described, 125 the combination of a rotatable screw shaft, a pinion mounted thereon for rotary movement therewith and longitudinal movement thereon, and reduction gearing intermediate 135

- such pinion and a part of the engine to be started, said gearing comprising a gear of larger diameter than the pinion and having a hub, a second pinion on the hub, and a 5 shaft on which said gear and hub rotate and also move longitudinally, the gear being arranged in the path of the first pinion for initial meshing therewith, then bodily movement thereby and final rotary movement 10 therewith.
11. In a drive of the character described, the combination of a rotatable screw shaft, a pinion mounted thereon for rotary movement therewith and longitudinal movement 15 thereon, and reduction gearing intermediate such pinion and a part of the engine to be started, said gearing comprising a gear of larger diameter than the pinion and having a hub, a second pinion on the hub, and a 20 shaft on which said gear and hub rotate and also move longitudinally, said first pinion being arranged in its longitudinal movement to mesh with the gear and having a projection adapted to contact with such gearing 25 and to move it and its pinion bodily longitudinally to bring the second pinion into mesh with the engine part, said first pinion being arranged in its rotary movement to drive the reduction gearing.
12. In a drive of the character described, the combination of a rotatable member, a 30 driving member mounted thereon for rotary movement therewith and longitudinal movement thereof, and reduction means which is operated and controlled by the driving member and which is adapted to be thereby 35 operatively engaged with a part of the engine to be started.
13. In a drive of the character described, the combination of a driving shaft, a rotatable member driven thereby, a driving member mounted thereon for rotary movement therewith and longitudinal movement thereof, a second shaft parallel with the 40 first-named shaft, and reduction means mounted on the second shaft for rotary movement thereon and longitudinal movement thereof, said means being operated and controlled by the driving member and adapted to be thereby 45 operatively engaged with a part of the engine to be started, and a spring for yieldingly holding the reduction means in an inoperative position.
14. In a drive of the character described, the combination of a driving shaft, a rotatable member driven thereby, a driving member mounted thereon for rotary movement therewith and longitudinal movement thereof, a second shaft, and reduction gearing 50 mounted on the second shaft for rotary movement thereon and longitudinal movement thereof, said gearing being operated and controlled by the driving member and adapted to be thereby operatively engaged with a part of the engine to be started.
15. In a drive of the character described, the combination of a driving shaft, a rotatable member driven thereby, a driving member mounted thereon for rotary movement therewith and longitudinal movement thereof, a second shaft parallel with the first-named shaft, reduction means mounted on the second shaft for rotary movement thereon and longitudinal movement thereof, said means being operated and controlled by the driving member and adapted to be thereby 55 operatively engaged with a part of the engine to be started, and means for yieldingly holding the reduction means in an inoperative position.
16. In a drive of the character described, the combination of a driving shaft, a rotatable member driven thereby, a driving member mounted thereon for rotary movement therewith and longitudinal movement thereof, a second shaft parallel with the first-named shaft, reduction means mounted on the second shaft for rotary movement thereon and longitudinal movement thereof, said means being operated and controlled by the driving member and adapted to be thereby 60 operatively engaged with a part of the engine to be started, and a spring for yieldingly holding the reduction means in an inoperative position.

VINCENT BENDIX.
